UNITED STATES PATENT OFFICE.

JOHN L. DAVIS AND LOUIS D. COOLEY, OF GREENVILLE, SOUTH CAROLINA.

LOOM ATTACHMENT.

Application filed February 13, 1922. Serial No. 536,124.

To all whom it may concern:

Be it known that we, JOHN L. DAVIS and LOUIS D. COOLEY, citizens of the United States, residing at Greenville, in the county of Greenville and State of South Carolina, have invented new and useful Improvements in Loom Attachments, of which the following is a specification.

This invention relates to an attachment for looms, and particularly to the picker stick actuating mechanisms of box looms of that type in which each picker stick is pivotally mounted upon a bracket, commonly called a picker foot, the said picker supporting brackets being mounted upon the opposite ends of the rocker shaft which is operatively connected with the swords of the lay.

In looms of this type as generally constructed, the picker sticks are connected by straps to a return spring or springs which are more or less lengthy and, by reason of their length and arrangement, cause more or less trouble and annoyance, besides being costly to replace and to keep in working condition.

One object of our invention is to provide means whereby this objection to the use of lengthy springs and straps is avoided and a type of return spring provided which is compact, arranged so as to be sheltered from injury and which is durable and, when damaged or broken, may be replaced at a comparatively low cost.

A further object of the invention is to provide a novel means for mounting the return spring upon a picker foot in such manner as to secure simplicity and compactness of arrangement as well as a mutual bracing between the picker supporting part of the picker foot and the spring support.

A still further object of the invention is to provide a novel type of supporting means and return spring for each picker stick, which spring may be adjusted to regulate its sensitiveness of action as required for use in connection with its particular picker stick.

The invention consists of the features of construction, combination and arrangement of parts, hereinafter fully described and claimed, reference being had to the accompanying drawings, in which:

Figure 1 is a sectional plan view of a picker foot, a picker stick and an improved return spring applied thereto, the plan of

section being indicated by the line 1—1 of Figure 2.

Figure 2 is a side elevation of the parts shown in Figure 1, and

Figure 3 is a perspective view of the spring 60 supporting bracket.

Referring to the drawings, 1 designates a portion of a side of a loom frame having journaled therein one end of a transverse rocker shaft 2, which shaft extends across the loom and is journaled at its opposite end in the opposite side of the loom frame and actuates the lay swords in a well known way. Each end of the shaft 2 carries a picker foot 3 for supporting the picker stick 70 4 at the adjacent side of the loom. In the present instance we have shown the mounting at one side of the loom only, it being understood that the same is duplicated at the opposite side of the loom.

As shown, the picker foot 3 is in the form of a substantially L-shaped bracket embodying a main arm 5 fixed at its inner end to the shaft 2 and extending outwardly substantially at right angles to the frame 1, 80 and a picker stick supporting arm 6 extending at a degree somewhat less than a right angle from the outer end of the arm 5 and in the same general direction and approximately parallel with the frame side 1. At 85 its outer or free end the arm 6 is provided with a bifurcated portion 7 extending at right angles to the frame and approximately parallel with the arm 5, through the slot of which bifurcated portion 7 the stick 90 4 extends. The side walls of this bifurcated portion 7 are properly pierced for the passage of a bolt 8 on which the picker stick 4 is pivotally mounted for reciprocating motion by any suitable type of actuating mechanism. A flange or web 9 preferably reinforces the bifurcated part from the arm 6 and is disposed in the space between said arm 6 and the adjacent wall of the bifurcation, and such flange 9 may serve for the 100 attachment thereto of a rod 10 connecting the picker foot with a part of the loom. A guide bracket 11 is secured to the inner side of the arm 5 by spaced bolts 12 and 13, and this bracket is formed with a guide eye 14 105 to receive the usual spring-controlled rod forming part of the shuttle box actuating means.

In accordance with our invention we provide a return spring bracket 15, preferably 110

made of cast metal. This bracket includes an outwardly projecting arm 16 which is disposed to lie against the outer ear of the bifurcation 7, and the body portion of this bracket lies flush against the inner or rear face of the supporting arm 6 of the main arm. The inner end of bracket 15 is formed with a rearwardly extending arm 17 which, when the device is applied, is disposed parallel with and in spaced relation to the main arm 5. The arm 17 is provided with an aperture 18 through which bolt 13 carried by arm 5 passes, to thus securely anchor the inner end of the bracket.

Extending rearwardly from the outer end of the body portion 15 of the return spring bracket is a leg member 19, offset slightly but disposed substantially parallel with the forwardly projecting arm 16. The lower end of this leg portion 19 is provided with an opening 20 to receive and rigidly maintain the shank 21 of a conventional type of spring-return drum 22. The opening 20 may be elongated as shown, to permit of necessary adjustment of the spring drum. This spring drum has secured to its surface one end of a strap or other flexible member 23; the opposite end of said member being connected to the lower end of the picker staff 4.

The bracket 15 is so constructed as to lie snugly against the offset portion 6 of the picker foot, and is rigidly secured thereto by bolts 8 and 13. The bracket thus properly reinforces the picker foot and is maintained thereon in such manner that breakage of either the bracket or the picker foot is rendered practically impossible. The leg 19 is so proportioned that the spring drum 22 held thereby will train the flexible strap or band 23 in substantially a horizontal line, whereby the maximum of efficiency of the spring retarding or retracting device is obtained. By reason of the elongated opening 20 in the leg, it is apparent that minute adjustment of the spring-return bracket may be made.

From the foregoing it is apparent that we have provided a device of extremely simple construction for effectively returning the picker staff to proper position without the use of objectionable coil and band springs heretofore used for similar purposes, and a device wherein the more delicate parts thereof are sheltered against injury. The particular construction of the bracket enables it to be readily applied to the main arm of looms of this type now in use, and the adjustment may be made without the exercise of unusual skill or intelligence.

Having thus fully described our invention, we claim:

1. The combination with a picker foot, said picker foot having an arm provided

with a forwardly projecting bifurcated portion, of a picker stick extending through said bifurcated portion, a bracket having a forwardly projecting arm bearing against one side of said bifurcated portion, and having a rearwardly projecting arm offset outwardly beyond the plane of but parallel with said forwardly projecting arm, a bolt passing through said forwardly projecting arm of the bracket and the bifurcated portion of the picker foot and fastening said bracket to said bifurcated portion and pivotally connecting the picker stick therewith, a supporting member carried by the rearwardly projecting offset arm of the bracket and extending inwardly in rear of the bifurcated portion of the picker foot, a spring drum carried by said supporting member, and a strap connecting said drum with the picker stick.

2. The combination with a picker foot, of a bracket shaped to conform to a portion of said picker foot and lying flush against the same, the said picker foot having a bifurcated portion to rockably support the picker arm, an arm on said bracket lying against said bifurcated portion, the said arm having an opening therein to correspond with the pivotal connection of the picker arm with said bifurcated portion, means for securing said bracket to said foot, a spring drum maintained by said bracket, and a flexible member connecting said drum with said picker arm.

3. The combination with a picker foot, the said picker foot having an offset member and a bifurcated portion to rockably support the picker arm, of a bracket shaped to conform to said offset portion of said bracket, a rearwardly extending arm at one end of said bracket disposed parallel to a portion of said picker foot, a bolt connecting said arm to said picker foot portion, a forwardly projecting arm at the other end of said bracket lying against a portion of said angularly disposed arm of said picker foot, the said forwardly projecting arm having an opening therein to receive the pivot bolt of a picker stick, a leg projecting rearwardly from said bracket, a spring drum supported by said leg, and a flexible member connecting said drum with said picker arm.

4. In an attachment for looms, a picker stick return spring supporting bracket including a straight body portion, an arm offset from one end of said bracket, an arm near the opposite end of said bracket projecting in a direction opposite to the first-mentioned arm and parallel with the latter, the said arms both having openings therein for passage of fastenings to secure the same to parts of a picker foot, a leg carried by said bracket and disposed parallel to the first-mentioned of said arms, the said leg being parallel with both of said arms and

spaced beyond the planes of the latter, and the said leg having a slot therein to receive a fastening for a return spring carrying member.

5 5. In a return spring supporting attachment for looms, a picker foot having an arm provided with a bifurcated offset projecting outwardly substantially at right angles to said arm, a bracket having a horizontally and forwardly projecting arm lying against one side of said bifurcated offset and a rearwardly projecting, vertically disposed leg, said arm and leg being connected by an offset portion disposing the same to lie in different vertical planes, the said bifurcated offset, arm and leg being formed with open-

ings, a bolt passing through the openings in the bifurcated offset and arm and fastening said arm to said offset, a picker stick pivotally engaging said bolt, a fastening member engaging the opening in the leg, and a return spring device supported by said fastening member and connected to the picker stick.

In testimony whereof we affix our signatures in presence of two witnesses.
